UNITED STATES PATENT OFFICE.

RICHARD KRAUSE AND LOU KRAUSE, OF NEW YORK, N. Y.

DESIGN FOR TEXTILE FABRIC.

SPECIFICATION forming part of Design No. 30,554, dated April 11, 1899.

Application filed January 9, 1899. Serial No. 701,689. Term of patent 3½ years.

To all whom it may concern:

Be it known that we, RICHARD KRAUSE and LOU KRAUSE, citizens of the United States, residing at New York city, in the county and State of New York, have invented and produced a new and original Design for Textile Fabrics; and we do declare the following to be a full, clear, and exact description of the same, reference being had to the accompanying drawing, forming a part thereof.

The accompanying drawing shows a portion of the goods with the design on it.

The leading or material feature of this design consists of groups of three narrow stripes running throughout the length of the piece of goods, and between the said groups of three stripes there are clusters of sprays of stems, leaves, and flowers.

In the drawing the three stripes are represented by letters *b*, *f*, and *b*. The two side stripes of the three, *b* and *b*, are of equal width. The figured design of sprays, &c., on the wide space between the stripes is represented by

c and *c'*. The object of this design is to have this particular figure *c* and *c'* placed on the fabric also in the style of a stripe running through the length of the piece in connection with the three narrow plain stripes and repeated throughout the breadth of the goods, so that the piece of goods can then be stripped or cut through the center of the stripe *f* into ribbons having a plain striped edge.

In making some of the figured spaces narrower, as *c'*, some of the central sprays are left out of *c*.

This design is applicable to printed or woven textile fabrics.

What we claim, and desire to secure by Letters Patent, is—

The design for textile fabric as herein shown and described.

RICH. KRAUSE.
LOU KRAUSE.
